CLAMP FOR APPLYING AND REMOVING
JAR COVERS

Edward N. Archer, Inglewood, Calif.

Application March 24, 1945, Serial No. 584,676

1 Claim. (Cl. 81—3.30)

1

My invention relates to a clamp adapted for gripping the lid of the jar in order that the jar may be manually operated relative thereto for the purpose of either applying or removing the lid or cover.

One of the objects of the invention is to provide means for supporting the jar in addition to gripping the cover thereof.

Another object of the invention is to provide a pair of cooperating gripping bands wherein at least one of such bands is provided with means to aid in supporting and gripping the jar while the other band is plain and more or less pliant and adapted for gripping purposes only.

Another object is to provide improved and simplified means for pivoting a flexible gripping band to a more or less rigid gripping band and for cooperatively connecting one band with the other to perform the desired operation.

Among other objects of the invention are to provide a clamp-holder of the above character which is more simple, easier to construct, and cheaper to manufacture.

Other objects, advantages and features of invention will hereinafter appear.

Referring to the accompanying drawing which illustrates what is now considered to be a preferred embodiment of the invention;

Fig. 1 is a perspective view of the device operatively applied to a jar lid, a fragment of a jar being included in the view and also a fragment of a wall being shown to which the device is fastened.

Fig. 2 is a plan view of the structure shown in Fig. 1, one of the gripping members of the holder being shown in dotted lines in the inoperative position as well as the means for securing both bands in their operative positions.

Fig. 3 is a section taken on line 3—3 of Fig. 2.
Fig. 4 is a section taken on line 4—4 of Fig. 3.

Fig. 5 is a section taken on line 5—5 of Fig. 1.

Referring in detail to the drawing, the stationary cover-gripping arm 6 includes a preferably straight shank portion 7, which at its outer end is welded or otherwise secured to a bracket 8 shown attached to a support 9 by means of screws 10. Said bracket is shown as a flat plate mounted in a vertical plane and having a vertical notch or slot 11 cut down into it from its upper edge into which is fitted the welded-on end portion of the jaw shank 7. The stationary arm 6 also includes an intermediate arcuate, preferably semi-circular, cover gripping jaw portion 12, which is internally provided with the transverse gripping teeth 13, and which, at the end thereof

2

opposite to its shank 7, is furnished with a straight radially projecting ear forming extremity 14.

The jaw extremity or radial ear 14 has cut 5 into it from its outer end a horizontal slot 15 and carries just below said slot an apertured lip 16 through which extends a pin 17, whereby a clamping bolt 18 is attached in such a manner as to swing through said slot, said lip being 10 located at the outer side of the extension 14, that is to say, at the convex side of the stationary jaw. The slotted ear connection enables clamp- 15 ing of the jays about covers of varying diameter. Along the lower edge of the arcuate jaw portion 12 are cut a series of notches, thereby producing intervening small flanges or lugs 19, which are directed horizontally inward, as well shown in Fig. 2. In the manufacture of the device the 20 inturning of this flange structure is facilitated by providing said notches.

With the stationary jaw which has been de- 25 scribed cooperates an arcuate movable jaw 20 which likewise carries at its free end a radial ear 21 having an end slot 22 wide enough to receive the clamping bolt 18, the winged clamp- 30 ing nut 23 being abuttable against the outer side of the extension 21. Said movable jaw 20 is not provided with gripping teeth nor with a serrated flange, and hence can be and preferably 35 is, made sufficiently flexible to conform to covers differing in diameter.

The attached end of the swingable jaw 20 has cut into it a slot 25, thus producing a bifurcation 35 each branch of which is outwardly curled as indicated at 26 to produce hinge ears, the stationary clamp portion 6 having a similarly curled tongue 27 outstruck from its midwidth portion to produce a hinge ear intermediate the ears 26, so that an inserted pin 28 completes the hinge 40 structure.

The rows of lugs 19 carried by the stationary 45 jaw forms an arcuate shelf which, when the device is clamped around a jar cover 30 functions as a shoulder means which underlies one side portion of the lower edge of the circumferential skirt of the jar cover. Said shelf or row of lugs is formed by inwardly deflecting the lower edge portion of the strap metal of which the stationary jaw is formed.

50 In using the device to remove a jar's cover, after the bracket 8 has been attached to the wall, thus supporting the stationary clamp arm 6 in a horizontal position as shown in Fig. 1, then the operator will use one hand to grip the jar and will 55 thus bring one side of the attached cover of an

upstanding jar into a nested relation to the teeth of the stationary jaw, while the clamping bolt 18 and movable jaw 20 are in the dotted line positions of Fig. 2. Then with his other hand the operator will swing the movable jaw against the adjacent side of the cover, thus bringing the slotted jaw extensions 14 and 21 sufficiently near to each other to permit a finger or the thumb of the latter hand to swing the nut-carrying bolt 18 to the full line position of Fig. 2. The shelf portion 19 will now support the jar so that the operator's first mentioned hand will be freed to screw down the clamping nut 23, whereupon both hands can be used bi-manually to unscrew the suspended jar from its cover; or to more tightly screw down a partly applied cover.

It should be understood that the present disclosure is for the purpose of illustration only and that this invention includes all modifications and equivalents which fall within the scope of the subject matter claimed.

What is claimed is:

A gripping and supporting clamp for a jar cover of the type having a circumferential skirt, said clamp comprising an arm having a substantially semi-circular flexible jaw portion, a shank extending radially outward of one end of the jaw adapted for connection with a support for holding said arm in fixed position, an ear projecting radially from the opposite end of the jaw, a complementary substantially semi-circular jaw having one end hingedly connected to said shank and an ear projecting radially from its opposite end, said fixed and hinged jaws cooperatively embracing the circumferential skirt of the jar cover, said fixed jaw having teeth extending transversely

thereof on its inner side for gripping the jar cover and having a plurality of lugs directed inwardly of its bottom edge so as to engage the bottom edge of the cover skirt, and means engaging said radial ears for releasably clamping the jaws about covers of varying diameter.

EDWARD N. ARCHER.
